(57) **CLAIM**

We claim the ornamental design for a offset hinge for ambulatory device, as shown and described.

DESCRIPTION

FIG. 1 is a front/right/top perspective view of a first embodiment of the offset hinge for ambulatory device.

FIG. 2 is a front elevational view of the first embodiment of the offset hinge for ambulatory device.

FIG. 3 is a rear elevational view of the first embodiment of the offset hinge for ambulatory device.

FIG. 4 is a top plan view of the first embodiment of the offset hinge for ambulatory device.

FIG. 5 is a bottom plan view of the first embodiment of the offset hinge for ambulatory device.

FIG. 6 is a right side elevational view of the first embodiment of the offset hinge for ambulatory device.

FIG. 7 is a left side elevational view of the first embodiment of the offset hinge for ambulatory device.

FIG. 8 is a front/right/top perspective view of a second embodiment of the offset hinge for ambulatory device.

FIG. 9 is a front elevational view of the second embodiment of the offset hinge for ambulatory device.

FIG. 10 is a rear elevational view of the second embodiment of the offset hinge for ambulatory device.

FIG. 11 is a left side elevational view of the second embodiment of the offset hinge for ambulatory device; the right side is a mirror image.

FIG. 12 is a top plan view of the second embodiment of the offset hinge for ambulatory device; and,

FIG. 13 is a bottom plan view of the second embodiment of the offset hinge for ambulatory device.

The broken line showings in the drawings are for illustrative purposes only and form no part of the claimed design.
